UNITED STATES PATENT OFFICE.

SOLOMON ROSOFSKY, OF BROOKLYN, N. Y.

WATCH-GUARD.

943,271.

Specification of Letters Patent. Patented Dec. 14, 1909.

Application filed March 26, 1909. Serial No. 436,042.

To all whom it may concern:

Be it known that I, SOLOMON ROSOFSKY, a citizen of the United States, residing at Brooklyn, in the county of Kings and State 5 of New York, have invented certain new and useful Improvements in Watch-Guards; and I do hereby declare the following to be a full, clear, and exact description of the invention, such as will enable others skilled 10 in the art to which it appertains to make and use the same, reference being had to the accompanying drawings, and to characters of reference marked thereon, which form a part of this specification.

15 The present invention has reference, generally, to improvements in safety-retainers or guards for watches and the like; and, the invention relates, more particularly, to a novel device which is adapted to be arranged 20 and secured within the pocket of wearing apparel to prevent the watch from being lost or stolen, but the device being of such a construction that the watch can be easily withdrawn by the wearer of the garment.

25 The invention has for its principal object to provide a simple and effective means for securing a watch in the pocket of a garment, and guarding the same against accidental or surreptitious removal therefrom; and, the 30 invention has for its further object to provide a novel means for detachably securing the safety-retainer or watch-guard in the pocket of the garment, as well as the provision of a novel means for locking said 35 safety retainer or watch-guard against the removal of the watch retained therein.

A further object of this is to provide a safety-retainer for watches which not only guards said watch from accidental or sur- 40 reptitious removal, but also provides a means for preserving the polished or engraved cases of the watches against scratching or marring, which is generally the result of carrying them in the pocket in the ordinary 45 way.

With the various objects of my present invention in view, the said invention consists, primarily, in the novel watch-guard herein- 50 after set forth; and, the invention consists, furthermore, in the several novel arrangements and combinations of the various devices and parts, as well as in the details of the construction thereof, all of which will be 55 hereinafter fully described and then embodied in the clauses of the claims which are

appended to and which form a part of this specification.

The invention is clearly illustrated in the accompanying drawings, in which:—

Figure 1 is an exterior view of the watch-pocket of a piece of wearing apparel or garment, the said view showing in dotted outline the position of a safety-retainer or watch-guard embodying the principles of my present invention. Fig. 2 is a rear view 60 of the inner side of said wearing apparel or garment adjacent to said watch-pocket, said view illustrating, more particularly, a novel means for securing said safety-retainer or watch-guard within said watch-pocket. Fig. 3 is a vertical cross-section, said section being taken on line 3—3 in said Fig. 2. Fig. 4 is a rear view of said safety-retainer or watch-guard removed from the pocket. Fig. 5 is a face view of the frame-work of said 75 safety-retainer or watch-guard, the covering of the same being removed. Fig. 6 is an end view of said frame-work; Fig. 7 is a perspective view of said frame-work, the covering of the same being shown in dotted 80 line; Fig. 8 is a detail face view of the frame-work of said safety-retainer or watch-guard, but illustrating in connection therewith a slightly modified form of locking device; and Fig. 9 is an enlarged horizontal 85 section of the same, said section being taken on line 9—9 in said Fig. 8, looking in the direction of the arrow α .

Similar characters of reference are employed in all of the said above described 90 views, to indicate corresponding parts.

Referring now to the said drawings, the reference-character 10 indicates a portion of a garment or wearing apparel provided with a watch-pocket 11 and a back or rear 95 lining 12. Arranged so as to slip into and to be arranged within the said watch pocket 11 is a safety-retainer or watch-guard, embodying the principles of my present invention, the same comprising a main frame 100 13, constructed preferably, of a single piece of wire, in the following manner. The said wire is bent upwardly at each end so as to form suitable side-frames 14, each side-frame thus formed being provided with a 105 perforated flattened portion 15. The opposite ends of said wire are then bent toward each other, so as to be parallel to each other, or substantially so, and extend each to the opposite side-frame 14, so as to form suit- 110

able mouth-frames 16, the free ends or portions 17 of said wire are then bent downwardly and are provided with perforated flattened portions 18 adapted to register 5 with the respective flattened portions 15 of said side-frames 14, said parts being pivotally connected together by means of a rivet or pintle 19 thus forming and completing a retaining frame comprising a pair of hinged 10 or pivotally connected frame-sections, as will be clearly evident. Owing to this peculiar construction of frame-work, the tendency of the mouth or opening of the same, due to the torsion of the wire of which said 15 frame-work is constructed, is always to remain open, when not held closed, by means of a locking device, which when released permits the frame-sections to automatically spring open, as will hereinafter appear. 20 The means for retaining said frame-sections in their closed or locked relations, to safely retain and guard a watch from being accidentally or surreptitiously removed from the pocket, consists, essentially, of a suitably 25 formed spring-arm 20 suitably secured to one of said flattened portions 18, or to any other suitable and convenient point. This spring-arm is provided at its upper end with a laterally extending member 21 formed at one end in a right angled 30 tongue or lug 22 adapted to always remain in sliding engagement with one of said side-frames 14, while the opposite end of said member is provided with a catch-piece or hasp, as 23, adapted to engage the adjacent end-portion 17 and hold the same. The means for releasing said catch-piece or hasp 23 comprises a push-button or finger-piece 24 connected by means of a shank 25 35 to the upper portion of said spring-arm 20, said shank 25 extending outwardly between said side-frame 14 and the adjacent end-portion 17. By pushing with the finger upon said push-button or finger-piece 24, the said spring-arm 20 is forced inwardly 40 thereby causing the said catch-piece or hasp 23 to release its hold upon said end-portion 17 so as to permit the frame-sections to spring apart and open the mouth of said 45 frame-work, as will be clearly evident. The said wire frame-work is covered to form a pocket 26 by means of a suitable fabric, said fabric being made in the form of a bag or pocket in which the watch is placed, and 50 which also serves as a protection against scratching or marring the polished or engraved surface of the watch which is retained therein. One means for securing said safety-retainer or watch-guard within 55 the pocket 11 of the wearing apparel or garment is shown more particularly in Figs. 2, 3 and 4 of the drawings. Secured upon the back of said pocket 26, hereinabove mentioned, by means of an inclosing-portion 60 of fabric 27 is an elongated-plate 28,

provided with outwardly extending shanks 29, which are located at a suitable distance from each other, and project through suitable perforations or holes in said inclosing portion of the fabric 27. Each shank 29 70 is provided with a suitable head 30.

When the safety-retainer or guard is placed within the pocket 11 of the wearing apparel or garment, these shanks 29 extend outwardly from the back thereof and the 75 heads 30 press against the pocket 11 and lining 12, substantially in the manner shown. A locking-bar 31 which is provided with a pair of side-bars, as 32, which are suitably joined together at their ends, provide a retaining device formed with an elongated opening or space 33, said bars 32 being made with outwardly bowed portions, as 34, which provide suitable receiving portions 35, which are arranged upon the previously mentioned shanks 29 in the following manner:—The heads 30 of said shanks 29, covered as they are with the fabric of said pocket 11 and the lining 12, are thrust through the said receiving portions 35 of 80 said locking-bar 31, the said bar 31 being then pushed sidewise so as to bring the shanks 29 into said elongated openings or spaces 35 so as to squeeze the fabric of said pocket 11 and lining 12 between said shanks 95 29 and said side-bars 32, with the head 30 of each shank 29 projecting over said side-bars 32 and thereby preventing the locking-bar from slipping outwardly and away from said shanks 29, the friction between the said 100 fabric and the shanks 29 and side-bars 32 being sufficient to prevent any return side-slipping of said locking bar 31. The safety-retainer or watch-guard being thus secured in operative position within the pocket 11 105 of said wearing apparel or garment, a watch is placed therein and the frame-sections are pressed together and held in their locked engagement by the locking-device hereinabove described, until the latter are released 110 by pressing the push-button or fingerpiece 24, thus securely retaining said watch against accidental or surreptitious removal.

Referring now more particularly to Figs. 8 and 9 of the accompanying drawings, there 115 is illustrated therein a slightly modified construction of locking device for locking said frame-sections 16 together. This modified device comprises a pair of horizontally extending tongues or members 36, one tongue 120 being secured to each side-frame 14 by means of rivets 37, or other suitable fastening means, said tongues terminating in a catch-piece 38 adapted to engage the respectively adjacent end-portions 17. Each 125 rivet 37 is provided with a shoulder 39 and an outwardly extending shank 40 formed at its free-end with a head or push-piece 41. By engaging said push-pieces 41 with the fingers and pressing the same toward each 130

other, the catch-pieces 38 are caused to release their hold upon said end-portion 17, thereby permitting the frame-sections 16 to spring apart and thus opening the safety-5 retainer or watch-guard to permit the removal of the watch from within the watch-guard and the pocket of the garment.

It will be clearly evident, that the watch may be used in the ordinary manner when 10 connected with a watch-chain, fob, or guard, since the latter will extend between the frame-sections 16 when closed since the space between them is sufficiently wide to permit the arrangement of such parts between the frame-sections, but the space not 15 being wide enough to allow the passage of the watch therethrough.

I am aware that changes may be made in the arrangements and combinations of the 20 various devices and parts, as well as in the details of the construction thereof, without departing from the scope of my present invention, as described in the foregoing specification and as defined in the claims appended thereto. Hence, I do not limit my 25 invention to the exact arrangements and combinations of the parts as herein shown and described, nor do I confine myself to the exact details of the construction thereof.

30 I claim:

1. A safety-retainer for watches comprising a covered frame-work provided with a self-opening mouth, a spring-arm secured to said frame-work, means connected with said 35 spring-arm for securing said mouth in its closed relation, a push-piece connected with said spring-arm for operating the same, and means for securing said covered frame-work within the pocket of wearing apparel, comprising an elongated plate, shanks upon said 40 plate, heads upon said shanks, means for securing said plate to said frame-work, and a locking bar adapted to engage said shanks and retain a pocket and wearing apparel in 45 holding engagement therewith, substantially as and for the purposes set forth.

2. A safety-retainer for watches comprising a covered frame-work, means for securing said covered frame-work within the 50 pocket of wearing apparel, comprising an elongated plate, shanks upon said plate, heads upon said shanks, means for securing said plate to said covered frame-work, and a locking-bar adapted to engage said shanks 55 and retain a pocket and wearing apparel in holding engagement therewith, substantially as and for the purposes set forth.

3. A safety-retainer for watches comprising a covered frame-work provided with a 60 self-opening mouth, means for locking said

mouth in its closed relation, and means for securing said covered frame-work within the pocket of wearing apparel, comprising an elongated plate, shanks upon said plate, heads upon said shanks, means for securing 65 said plate to said covered frame-work, and a locking bar adapted to engage said shanks and retain a pocket and wearing apparel in holding engagement therewith, substantially as and for the purposes set forth.

4. A safety-retainer for watches comprising a wire frame-work provided with side-frames, a pair of parallel frame-portions between said side-frames, and end-portions pivotally connected with said side-frames, a 70 catch-member adapted to secure said frame-portions in their closed relation, a flexible covering secured upon said frame-work, comprising an elongated plate, shanks upon said plate, heads upon said shanks, means for securing 75 said plate to said covered frame-work, and a locking bar adapted to engage said shanks and retain a pocket and wearing apparel in holding engagement therewith, substantially as and for the purposes set forth.

5. A safety-retainer for watches comprising a wire frame-work provided with side-frames, a pair of parallel frame-portions between said side-frames, and end-portions pivotally connected with said side-frames, the members of said frame-work being formed integrally one with the other, a 80 spring-arm secured to one of said side-frames, a tongue connected with said spring-arm, said tongue being adapted to engage 85 said side-frame, a catch-piece connected with said spring-arm for retaining the frame-sections in their closed relation with each other, a shank provided with a push-piece connected with said spring-arm and adapted to operate said spring-arm to release said catch-piece, a flexible covering secured upon 90 said frame-work, and means for securing said covered frame-work within the pocket 95 of wearing apparel, comprising an elongated plate, shanks upon said plate, heads upon 100 said shanks, means for securing said plate to said covered frame-work, and a locking bar adapted to engage said shanks and retain a 105 pocket and wearing apparel in holding engagement therewith, substantially as an 110 for the purposes set forth.

In testimony that I claim the invention set forth above I have hereunto set my hand 115 this 23rd day of March, 1909.

SOLOMON ROSOFSKY.
